UNITED STATES PATENT OFFICE.

GUSTAF B. ANDERSON, OF CHICAGO, ILLINOIS.

PNEUMATIC ATTACHMENT FOR CHAIRS.

SPECIFICATION forming part of Letters Patent No. 739,972, dated September 29, 1903.

Application filed December 30, 1901. Serial No. 87,741. (No model.)

To all whom it may concern:

Be it known that I, GUSTAF B. ANDERSON, a subject of the King of Sweden and Norway, residing at Chicago, in the county of Cook and 5 State of Illinois, have invented certain new and useful Improvements in Pneumatic Attachments for Chairs, of which the following is a specification.

This invention relates to improvements in 10 an apparatus to be used for compressing and discharging air under pressure, and while it is more especially intended to be used in connection with or as an attachment to a rocking-chair for cooling the face of the occupant, yet 15 it is applicable to other kinds of chairs or frames and for other purposes where air under pressure is required; and it consists in certain peculiarities of the construction, novel arrangement, and operation of the various parts 20 thereof, as will be hereinafter more fully set forth and specifically claimed.

The principal object of my invention is to 25 provide a simple and inexpensive apparatus for compressing air and discharging it in one or more jets while under pressure and also to furnish an apparatus of the above-described character in which the air may be compressed by the rocking of a chair.

Other objects and advantages of the invention 30 will be disclosed in the subjoined description and explanation.

In order to enable others skilled in the art 35 to which my invention pertains to make and use the same, I will now proceed to describe it, referring to the accompanying drawings, in which—

Figure 1 is a view in side elevation of a rocking-chair with an attachment embodying my invention applied thereto and showing the 40 parts in position ready for operation. Fig. 2 is an enlarged view of the lower portion of the bellows and a part of its support, showing the latter shortened for the convenience of illustration. Fig. 3 is a plan view of a portion of 45 said support. Fig. 4 is a central sectional view taken on line 4-4 of Fig. 1 through the air discharger or distributor shown in said figure. Fig. 5 is an enlarged longitudinal sectional view of the air-controller or handpiece, 50 showing it provided with another form of air-discharger. Fig. 6 is a view, partly in section and partly in elevation, taken on line 6-6 of

Fig. 5 looking in the direction indicated by the arrows. Fig. 7 is a longitudinal view, partly in section and partly in elevation, of a 55 portion of said handpiece or air-controller, showing still another form of an air-discharger connected thereto; and Fig. 8 is a cross-sectional view of the bellows, taken on line 8-8 of Fig. 1. Fig. 9 is a perspective view of a modification in the form of the frame or support for the bellows and in the means for operating the same, and Fig. 10 is a view in side elevation of the operating-lever therefor.

Similar letters refer to like parts throughout the different views of the drawings.

A represents a rocking-chair, which may be of the ordinary or any preferred construction and as usual is provided with a pair of rockers *a* on its lower portion. Located between the rockers *a* of the chair and its side uprights *a'* is a bellows *B* of the well-known type, the bottom of which rests on and is supported by a bar *C*, which extends longitudinally and about midway between the rockers 75 and has on each of its ends a roller or caster *c* to cause the chair to roll easily over the carpet or floor. A portion *b* of the frame of the bellows *B* is connected to each of the rockers by means of pieces *b'*, located near the front 80 and rear ends of the bellows. The portion or partition *b* divides the bellows into two compartments *B'* and *B*², the former being used as a storage-reservoir and the latter as a pump or compressor. The bottom of the 85 portion *B*² is provided with inlet-valves, and the portion *b* or partition is also provided with a valve or valves to allow the air to pass into the reservoir. Resting on the top of the bellows or the reservoir portion *B'* thereof and 90 against the lower surface of the chair-seat *a*² are springs *d*, which tend to press the upper portion of the bellows downwardly, thus holding the air therein under pressure. Projecting downwardly from the middle portion of 95 the chair-seat *a*² is a pin *d'*, which when the upper portion of the bellows is raised by inflation will contact with the valve *d*² in the top of the bellows and allow some of the compressed air to escape. The lower portion *B*² 100 of the bellows is employed as a pump or compressor, while the upper portion *B'* is used as a reservoir, as is apparent. Connected to the bellows and communicating with its reservoir

is one end of a tube D, to the other end of which is secured the handpiece or air-controller E, which is preferably made of two pieces e and e' , secured together by means of 5 glue or otherwise. This handpiece or air-controller is formed with channels e^2 and e^3 and with tubular portions e^4 and e^5 to engage a tube or flexible hose D and the air-discharger, respectively. The inner surface of 10 the piece e' has hinged thereto a valve e^6 , which is actuated by means of a spring e^7 , and opens and closes the inner end of the channel e^3 , as is clearly shown in Fig. 5 of the drawings. Extending through the piece e' 15 and connected at its inner end to the valve e^6 is a rod or stem f , which has on its outer end a button or head g , provided on its inner surface with a piece of felt g' to close the opening through which the stem passes when the button 20 is pressed inwardly. Between the valve e^6 and the outer portion of the channel e^3 and located on the stem f is a piece h , which also prevents the escape of air through the opening in which the stem f operates. Located on one end of 25 the handpiece or air-controller E and communicating with the channel e^3 thereof is a hollow air-discharger II, which in Figs. 1 and 4 of the drawings I have shown as being in the shape of a circular fan and as having on 30 one of its faces a series of perforations h' , through which the air may be discharged while under pressure in a large number of small jets. In Figs. 5 and 7 of the drawings I have shown modified forms of the air-discharger, which comprise hollow or tubular pieces II' and II'', contracted at their outer ends 35 so as to form small orifices h^2 and h^3 , through which the air will be discharged with great force.

40 In Fig. 9 of the drawings I have shown a modification in the construction of the frame which supports the bellows and in the means for operating the same, which consists of a frame A', between the uprights of which is located the bellows B, which comprises a reservoir B' and a pump or compressing portion B'', as in the above-described construction. Fulerumed on the lower portion of the frame A' is a foot-lever I, which is connected 45 at its inner end by means of a link L to the bottom of the bellows and which is actuated by means of a spring m, secured to the lower portion of the supporting-frame, as is clearly shown in Fig. 9 of the drawings. In this construction the frame A' is provided, as before, with springs d, which rest on the upper surface of the reservoir of the bellows and against the lower surface of the top of the frame. Connected to the bellows is a tube or hose D, 50 which is equipped at its outer end with a handpiece or air-controller E, as in the other construction, and which handpiece may have connected thereto one of the air-dischargers shown in Figs. 5 and 7 of the drawings, or, if

desired, an air-discharger of the form shown 65 in Figs. 1 and 4 of the drawings.

From the foregoing and by reference to the drawings it will be seen and clearly understood that when the construction illustrated in Fig. 1 is employed by rocking the 70 chair back and forth the front and rear lower portion of the bellows will be alternately raised and lowered by reason of its connection with the rockers through the medium of the strips or pieces b', while the bottom of 75 the bellows will remain in a fixed or stationary position on account of its being secured to the bar C, thus causing the reservoir B' to be inflated or filled with air under pressure, which may be allowed to escape through any 80 of the air-dischargers, and thereby direct it to any portion of the face or person. It is apparent that by pressing the button g inwardly the valve e^6 will be opened to allow the air to pass through the tube D from the 85 bellows and out through the perforations or orifices of the air-discharger. When the construction shown in Fig. 9 is employed, the same operation is performed, except that the compression of the air is effected through 90 the medium of the lever I, which may be operated by the foot, as is evident.

Having thus fully described my invention, what I claim as new, and desire to secure by Letters Patent, is—

1. The combination with a rocking-chair provided with a downwardly-projecting pin on its seat, of a bellows located within its frame and connected near its front and rear ends to each of the rockers of the chair, said bellows comprising a pumping portion and a reservoir having an inwardly-opening valve to contact with said pin, springs located between the upper portion of the bellows and the seat of the chair, a support horizontally 105 and rigidly secured to the bottom of the bellows and having at each of its ends rollers to rest on the floor, a hose communicating at one of its ends with the reservoir, an air-controller or handpiece on the other end of 110 said hose, substantially as described.

2. The combination with a frame having in its upper portion a downwardly-projecting pin, of a bellows having in its top an inwardly-opening valve to contact with said pin, means 115 to operate the bellows, a flexible tube or hose communicating at one of its ends with the bellows, an air-controller or handpiece on the other end of said tube, said controller being channeled and provided with a hinged 120 leaf-valve to open and close the same, a spring to normally close said valve, and an air-discharger connected to the said controller, substantially as described.

GUSTAF B. ANDERSON.
